4 Sheets-Sheet 2

<img alt="A detailed technical cross-sectional diagram of a mechanical system, likely a pump or compressor, showing various components and numbered parts. The diagram includes a top header with five small circular components, a central vertical pipe assembly with several valves and fittings, and a base structure with horizontal beams and supports. Numerous parts are labeled with numbers such as 5, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 229, 230, 231, 232, 233, 234, 235, 236, 237, 238, 239, 239, 240, 241, 242, 243, 244, 245, 246, 247, 248, 249, 249, 250, 251, 252, 253, 254, 255, 256, 257, 258, 259, 259, 260, 261, 262, 263, 264, 265, 266, 267, 268, 269, 269, 270, 271, 272, 273, 274, 275, 276, 277, 278, 279, 279, 280, 281, 282, 283, 284, 285, 286, 287, 288, 289, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, UNITED STATES PATENT OFFICE.

AUSTIN L. WERTZ, OF PHILADELPHIA, PENNSYLVANIA.

TANK-VEHICLE CONSTRUCTION.

Application filed May 12, 1923. Serial No. 638,478.

To all whom it may concern:

Be it known that I, AUSTIN L. WERTZ, a citizen of the United States, residing at Philadelphia, county of Philadelphia, and

5 State of Pennsylvania, have invented certain new and useful Improvements in Tank-Vehicle Constructions, of which the following is a specification, reference being had to the accompanying drawings.

10 My invention relates generally to the construction of tanks and their mountings, but considered from a more specific viewpoint, to the mounting of tanks upon motor vehicles of the type useful for example in transporting and dispensing of gasoline, lubricating oils or other liquid commodities.

In the latter connection, it has heretofore been customary to employ single tanks with dividing partitions at intervals in them to 20 provide separate and distinct compartments in order that a number of different liquids could be carried at the same time, or the same liquid in different quantities to obviate subsequent measuring at the points of delivery. Such tanks were open to several objections amongst which may be mentioned the difficulty of maintaining the different compartments against cross leakage and the necessity in many instances for discarding 25 an entire tank in the case of damage to any part of the same incurred as a result of collisions or road shocks.

The main object of my invention is to overcome the difficulties to which reference 30 has been made, and this I accomplish by provision of a tank organization constituted of a number of composite units complete in themselves, adapted to be arranged end to end in a series, and standardized as to dimensions for interchangeability when substitution should be required as a result of an accident or for the purpose of effecting a 35 change in relative unit capacities.

My invention is further directed toward 40 provision of means whereby the units aforesaid are secured one to the other and to the tank support in such manner as to insure them against possible displacement, yet allowing sufficient flexibility for compensative self-adjustment so as to better withstand strains likely to be imposed upon them 45 during travel of the vehicle.

How these and other subsidiary objects, together with their attendant advantages 50 may be obtained will become readily apparent from the detailed description, which

follows, of a typical embodiment of my invention; while the appended claims clearly define the scope of my invention in so far as it comes within my present knowledge. 60

In the drawings Fig. I is a side elevation of a tank vehicle characterizing the novel features of my invention.

Fig. II is an inverted plan view of the superstructure of the vehicle, the chassis of 65 the latter having been omitted to avoid obscuring of certain important details.

Fig. III is a rear elevation of the vehicle showing more particularly the storage receptacle or box attached at the end of the 70 tank.

Fig. IV is a cross-sectional elevation of the vehicle.

Fig. V is a detail view on an enlarged scale with parts broken away and condensed, 75 showing the construction of the units constituting the tank organization, and the manner in which such units are secured to the supporting frame of the superstructure; and

Fig. VI is a view similar to Fig. V showing the manner in which the box, or storage receptacle is secured to the rearmost tank unit and to the supporting frame. 80

In the illustrations, the chassis of the vehicle is shown as comprising the usual frame 85 1 and rear wheels 2 together with other parts of the chassis which, having been omitted from the drawings, may be of any standard or approved design, and need not therefore be further described in detail here- 90

in. Mounted upon the chassis frame 1 and rigidly secured thereto, is a superstructure which includes an auxiliary frame comprehensively indicated by the numeral 3, said frame serving as the mounting for a tank 4 95 composed of a series of consecutively arranged units 5, 6 and 7. The auxiliary frame 3 also serves to support, at the rear of the vehicle, a receptacle or box 8 provided for storage of buckets, funnels and 100 other accessories ordinarily used in connection with dispensing of liquid commodities.

As shown, the auxiliary frame 3 includes a number of main members or sill beams 9 preferably timbers having an oblong cross-section as best seen in Fig. III. These sill beams 9 extend longitudinally of the chassis frame 1 and are directly supported upon the side rails 10 of the latter, see Fig. I. 105 The auxiliary frame 3 further includes a multiplicity of lateral or cross-members in the form of structural I-beams 10 which

bridge the longitudinal sill beams 9 as clearly shown. These lateral beams 10 are secured to the sill beams 9 by bolts 11 which pass through the bottom flanges 12 of said 5 lateral beams, and engage straddle clamp plates 13 seated in appropriate recesses or notches 14 in the lower faces of the sill beams 9. At the center, the transverse beams 10 are concaved to conform with the 10 roundness of the tank 4, and in each instance the concaved portion is topped by a corresponding arcuate segment 15 having its side edges symmetrically disposed relative to the vertical web of the I-beams and 15 rolled to afford terminal ridges 16-16. These arcuate segments 15 may be secured to the lateral beams in any convenient manner as for example by welding along the contacting surfaces as suggested conventionally at 17 in the drawings. If the 20 lateral beams 10 should be constructed as forgings the segments 15 could obviously be made continuous with the top flanges 17. If desired, the transverse beams of the 25 frame 3 may be extended at opposite sides of the vehicle as clearly shown in Figs. III and IV, for the purpose of sustaining enclosed overhang platforms 18 such as are ordinarily used in vehicles of this type for 30 the accommodation of cans or other vessels in which smaller quantities of the liquid commodities may be stored.

From the above it will be seen that the auxiliary frame 3 acts in the capacity of a 35 cradle support for the tank 4 which as shown in Figs. IV and V is made elliptical in cross-section with the major axis of the ellipse disposed horizontally. The elliptical form is preferred to the circular for the 40 reason that it is more stable under lateral motion of the vehicle during travel over rough roads, and further because it is advantageous in offsetting the tendency of the liquid contents to roll independently and 45 disturb the equilibrium of the structure generally. Surging of the contents of the tank in a direction longitudinally of the vehicle is offset, and to a great extent prevented by interposition, at intervals lengthwise of 50 the component tank units, of baffle plates having the irregular outline indicated at 19 in Fig. IV, so that suitable intervals are afforded intermediate the points of attachment whereby free communication may take 55 place between the subdivisions set up in the tank units and to permit complete drainage from a single outlet in each.

Pausing at this juncture to study the 60 specific construction of the tank units, from Fig. V it will be observed that the ends of their shells 20 are closed by heads 21, each formed with a laterally extending peripheral flange 22 adapted to seat against an annular, inward protuberance 23 directly 65 adjacent the corresponding end of the shell

of the tank unit. Such a protuberance 23 may be formed as the result of swedging an annular groove or depression 24 which is in turn used for a purpose to be hereinafter explained. After placing the head 21 within the end of the shell 20, the edge of the latter is rolled inward so as to overlap intimately, a substantial margin of the head, and the joint is thereafter sealed fluid-tight by welding as suggested at 25. By this method of construction and arrangement, the weld joint 25 is entirely free from strains and therefore not likely to be ruptured as invariably happens with corner joints. Moreover, by reason of its position 70 the welded joint 25 is appropriately protected from injury through impact. 75

Again referring to Fig. V, and also to Fig. I, it will be observed that each transverse or cradle beam 10 except the rearmost one (for a reason which will presently become apparent) serves to support the contiguous ends of a pair of adjacent tank units, and that the rolled portions 16 of the saddle segments 15 correspond with the perimetrical depressions or grooves 24 of the tank shells 20 so as to be capable of interengaging with them and thereby prevent displacement of the tank units relative to one another and to the supporting frame 3. In order to compensate for any irregularities or inaccuracies between the general curvature of the tank units 5, 6 and 7 or that of the saddle segments 15, and also to prevent direct metallic contact, I prefer to interpose between them a layer 26 of suitable packing material such for example as felt. Such packing functions in the additional capacity to protect the tank unit ends 21, 21 to a certain extent, against shocks incident to vehicular travel. 90

The ends of contiguous tank units 5, 6 and 7, are tied continuously together through the aid of connecting segments 27 which serve as complements to, and cooperate with the saddle segments 15 of the lateral frame beams 10, and with the same, constitute complete perimetrical enveloping bands. As will be apparent from further cursory examination of Fig. V, the cross-section of the complementary segments 27 is identical to that of the saddle segments 15 of the transverse beams 10, their rolled portions being adapted to engage the remaining portions of the perimetrical depressions or grooves 24 approximate the tank ends. The interruptions between segments 15, 27 which constitute the connecting bands are bridged by draw or tension bolts 28, said bolts extending through tubular ears 29 and 30 respectively welded or otherwise appropriately secured to said segments 15, 27, see Fig. IV. In this way the tank units 5, 6 and 7 are not only continuously connected together but at the same time secured to the transverse mem- 110 115 120 125 130

bers 10 of the supporting frame 3. In the latter function the connecting bands are assisted by straps 31 which are appropriately configured in cross-section to embrace the supplemental connecting segments 27 previously referred to, said straps 31 in turn enveloping the greater portion of the tank periphery and having their opposite ends formed with belt prolongations 32 adapted to be secured to fixed anchorages 33 at opposite sides of transverse beams 10.

One departure or exception is made to the general construction and mounting of the tank units 5, 6 and 7, as hereinbefore described, and this in connection with the unit 7 whose rear end, see Fig. VI, instead of being provided with but the single groove 24 affording the abutment for its head, has a second perimetrical groove 35 spaced from the first to correspond with the spacing of the edge ridges 16 of the segment 15 associated with the rearmost transverse beam 10 so that the back end of the unit 7 is wholly supported by the said transverse beam, a layer of packing 26 being interposed, as before, for the reason already understood. The illustration last referred to further shows that the shell 36 of the bucket compartment 8 is coupled directly to the rear end of the tank unit 7 said shell being provided at its inner end with a rolled edge 37 adapted to fit between the rolled edge of the supplemental segment 27 and the hold-down strap 31 whereby the rear end of the tank unit 7 is secured against displacement upon the auxiliary supporting frame 3. The upper portion of the bucket compartment 8 is of course arched or rounded as clearly shown in Fig. III to conform with the curvature of the tank and to make possible the interposition of the inner end of its shell 36 between the segment 27 and the hold-down strap 31 as noted. Otherwise the bucket compartment 8 may have any desired construction. For example, it may be swedged as at 39—40 to provide abutments for its front and rear walls 41—42, the latter of the two having hinged doors 43 whereby access may be had to the interior of the compartment 8. As a means of protection against possible denting, the compartment 8 may be lined with wood or other suitable material as suggested at 44 in Fig. VI.

The tank units 5, 6 and 7, may of course be made in different sizes, as will be apparent from comparison of the one marked 5 with the others. The larger tanks exemplified as at 5, for convenience of standardization and for the purposes of ready interchangeability with, or substitution for the others, are preferably made of a length representing an exact multiple of that of the smaller ones 6, 7. If the length of the larger tank unit 5 should warrant it, they may be provided as shown in Fig. I with in-

termidate hold-down straps 31^a detachably anchored to the transverse beams 10 of the frame 3 in the same manner as the others previously described. The customary adjuncts essential to the individual tank units 70 are also provided, these including a man hole cover 45 with an appropriately protected fill opening 46, and an emergency valve 47 of an approved or standard type. Each tank unit 5, 6 and 7 furthermore has 75 a gravity outlet 50 (see Fig. II) in communication with a suitable double drain pipe 51, the latter extending to a convenient point at the rear of the vehicle and there provided with suitable draw-off valves 80 52. The several valves are protected against injury by a bumper 53 extending laterally across the vehicle and secured to the auxiliary frame 3.

The method of mounting and securing together the component units of the tank 4, as hereinbefore described, will obviously not impose absolute rigidity. Accordingly, compensative adjustment may take place to a limited extent, at different points along the 85 tank organization, such as will assist in preventing rupture or other injury, and therefore promote longevity of the structure as a whole. Furthermore my improved construction facilitates ready interchange of 90 tank units, and injury to one will not necessarily impair the usefulness of the others so that the vehicle may even be employed with a faulty unit until replacement can conveniently be made. 100

Having thus described my invention, I claim:

1. A structure of the character described including a tank comprising component, interchangeable flangeless units arranged end to end, and a mounting frame affording transverse members each adapted to directly support the contiguous flangeless ends of a pair of adjacent tank units, the unit ends and the transverse members being complementarily ridged and recessed for inter-engagement to prevent displacement of the tank units relative to each other and to the mounting frame. 105

2. A structure of the character described including a tank comprising a series of component, interchangeable flangeless units arranged end to end in juxtaposed relation, connecting means in the form of perimetrical bands extending about and overlapping contiguous flangeless ends of adjacent tank units, said bands having rolled edges affording ridges for inter-engagement with corresponding perimetrical grooves adjacent the unit ends, a support for the tank, and means for securing the tank to the support. 115

3. A structure of the character described including a tank comprising a series of component flangeless units arranged end to end, a supporting frame affording transverse 120

members respectively adapted to directly support the contiguous flangeless ends of adjacent units, each of said members being formed with a saddle segment with rolled edges affording ridges for inter-engagement with corresponding perimetrical grooves adjacent the unit ends, and detachable, counterpart complemental segments likewise overlapping the contiguous unit ends and similarly rolled to engage the remaining portions of the aforesaid perimetrical grooves, and means for securing the tank to the support.

4. A structure of the character described including a tank comprising a series of component flangeless units arranged end to end, a supporting frame affording transverse members respectively adapted to directly support the contiguous flangeless ends of adjacent units, each of said members being formed with a saddle segment having rolled edges affording ridges for inter-engagement with corresponding perimetrical grooves adjacent the unit ends, detachable, counterpart complemental segments likewise overlapping the contiguous tank ends and similarly rolled to engage the remaining portions of the aforesaid perimetrical grooves, means for securing the tank to the support, and hold-down straps of arched cross-section adapted to embrace the complemental segments, said straps enveloping the greater portion of the tank perimeter, and having their opposite extremities anchored to the supporting frame so as to prevent lateral displacement of the tank on, said frame.

5. A structure of the character described including a tank comprising a series of component interchangeable flangeless units arranged end to end, a cradle frame for the tank affording a number of transverse con-

caved I-beams having the upper flanges longitudinally rolled to directly support the contiguous flangeless and annularly recessed ends of a pair of adjacent tank units, hold-down straps embracing the greater portion of the tank perimeter with the longitudinal edges inwardly rolled and respectively overlapping the contiguous ends of adjacent tank units supported by the transverse beams aforesaid, and said straps having their extremities anchored to the cradle frame so as to prevent lateral and longitudinal displacement of the tank on the frame.

6. A structure of the character described including a flangeless tank, a support for the tank, a storage compartment aligned with the tank at one end and made continuous therewith through marginal overlapping of their respective shells, and a tie strap enveloping the overlap, said strap having its ends anchored to the support so as to secure the tank and storage compartment to each other and to the support.

7. A structure of the character described including a flangeless tank, a support for the tank, a storage compartment aligned with the tank at one end and made continuous therewith through marginal overlapping of their shells, a ridge formed in one shell and adapted to engage a corresponding recess in the other within the margin of overlap to prevent relative displacement of the tank and said storage compartment, and a tie strap enveloping the overlap to maintain the connection aforesaid between the tank and the compartment and to secure the two to the support.

In testimony whereof, I have hereunto signed my name at Philadelphia, Pennsylvania, this 10th day of May, 1923.

AUSTIN L. WERTZ.
